UNITED STATES PATENT OFFICE.

OWEN T. SNYDER, OF COLUMBUS, OHIO.

LUBRICATOR FOR ELEVATOR-GUIDES.

1,017,331.

Specification of Letters Patent. Patented Feb. 13, 1912.

Application filed June 23, 1911. Serial No. 635,000.

To all whom it may concern:

Be it known that I, OWEN T. SNYDER, a citizen of the United States, residing at Columbus, in the county of Franklin and State of Ohio, have invented a certain new and useful Improvement in Lubricators for Elevator-Guides, of which the following is a specification.

The object of this invention is to provide a lubricator more especially for the guides of elevators said lubricator being of simplified and improved construction and adapted to effect an economy of the lubricant and also promote cleanliness.

15 The invention is embodied in the example shown in the accompanying drawing and set forth in the following description, the features of novelty being pointed out in the appended claims.

20 In the said drawings Figure 1 is mainly a vertical elevation of the oil distributing end of the device, one side being partly in section to illustrate interior details. Fig. 2 is a top plan view showing the device associated with an elevator guide, the latter being shown in horizontal section. Fig. 3 is a view in side elevation with the upper portion of the oil box in section. In this view there is also shown a fraction of the 25 elevator carriage and guide rail. Fig. 4 is a detail view on a magnified scale of the wick holder with portions of the construction in section.

In the views 5 designates the box to contain the oil as shown, said box being recessed in one of its vertical sides as seen at 35 5^a to extend around three sides of the usual guide rail 6. (See Fig. 2.)

7 is a strip of spring metal bent at its 40 upper end to extend over the upper edge of the wall of the box. This spring is secured at its upper end by a screw 7^a tapped into a projection 5^b cast with the box. Secured by means of a rivet 8^a to the outer or lower 45 end of the spring 7 is a block or piece 8 of impervious or non-absorbent material as for example hard fiber, or compressed paper pulp such as is now common on the market. Secured by the same rivet 8^a to the spring

50 7 is also a strip of lamp wick 9 which extends upward over the face of the spring and the upper edge of the box into the interior of the latter and the oil therein. The block 8 is recessed where the wick fits 55 against it (see Fig. 4) so that the surface of the block and wick are substantially flush,

the purpose being to have the block bear against the guide and the wick only lightly if at all. In this way only small but nevertheless sufficient portions of the lubricant, 60 are removed as the box travels up and down the guide. To make the block fit squarely against the guide when the box is applied thereto the spring 7 can be bent suitably, as seen at 7^c so that the face of the block shall stand vertical when held out by the guide. There are three of these lubricating wicks and the described holders therefor. They are held in place by small set screws as seen at 10. The springs 7 are so formed that the blocks bear with a light pressure on the rail when the box is applied thereto.

15 designates a disk opposite projection 5^b to bear upon the wick to control the flow of oil. The pressure of this disk is regulated by a screw in the wall of the box.

The oil box is shown as provided with a cover at 11 hinged to the rear edge of the box as at 12, 12. The box is secured to the elevator carriage on a rod 13 secured at its 20 foot by means of a bolt 14 and nut 15^a. The box is secured on the rod by means of set screw 16 passed through a lug 5^c on the box.

As the box traverses the guide the oil is drawn by capillary attraction through the 25 wick up over the wall of the box and down to supply the face of block 8. The block 8 is of little or practically no absorptive capacity and as it becomes dry fresh oil is supplied by the wick. Not only does this 30 construction economize the oil but it also wears well because of the hard nature of the block.

What I claim is:

1. In a lubricator of the kind described, 95 the combination with an oil box or reservoir, of a spring consisting of a strip of spring metal secured at its upper end to the upper portion of the box, said spring containing at its lower end a block of non-absorbent material to be yieldingly held by the spring against the part to be lubricated, and a wick extending from the interior of the box over and adjacent to said spring and to said block.

2. In a lubricator of the kind described, 100 the combination with an oil box or reservoir, of a spring consisting of a strip of spring metal secured at its upper end to the upper portion of the box, said spring containing at its lower end a block of non-absorbent material and a recess to receive 105

the wick, said block to be yieldingly held by the spring against the part to be lubricated, and a wick extending from the interior of the box over and adjacent to said 5 spring and into the recess of said block.

3. In a lubricator of the kind described, the combination with an oil box or reservoir, of a spring bearing at its lower end a block of non-absorptive material and a wick

leading from the interior of the oil box 10 thereto, said block being recessed to receive the wick so that the latter extends substantially flush with the face of the block.

OWEN T. SNYDER.
